(57) **CLAIM**

The ornamental design for a beverage container and lid, as described and shown.

DESCRIPTION

FIG. 1 is an exploded side view of a beverage container and lid showing our new design;

FIG. 2 is a side perspective view of the beverage container and lid;

FIG. 3 is a top plan view thereof;

FIG. 4 is a side view of the lid portion of the beverage container and lid of both embodiments with the beverage container portion removed for ease of illustration;

FIG. 5 is an opposite side view thereof;

FIG. 6 is a side view of the beverage container and lid, the opposite side being a mirror image thereof;

FIG. 7 is an exploded side view of a beverage container and lid showing a second embodiment of my new design;

FIG. 8 is a side perspective view of the second embodiment of the beverage container and lid;

FIG. 9 is a top plan view thereof;

FIG. 10 is a side view of the second embodiment of the beverage container and lid, the opposite side being a mirror image thereof;

FIG. 11 is a bottom plan view of the first embodiment of the beverage container and lid; and,

FIG. 12 is a bottom plan view of the second embodiment of the beverage container and lid.
